Primary Examiner — Sandra Snapp**CLAIM**

(57) I claim the ornamental design for a lounge chair, as shown and described.

DESCRIPTION

FIG. 1 is a front perspective view of a lounge chair, according to one embodiment;

FIG. 2 is a right side view of a lounge chair of FIG. 1, the left side view is a mirror image of the right side view of FIG. 2; FIG. 3 is a front view of a lounge chair of FIG. 1;

FIG. 4 is a rear view of a lounge chair of FIG. 1;

FIG. 5 is a top view of a lounge chair of FIG. 1; and,

FIG. 6 is a bottom view of a lounge chair of FIG. 1.

The dashed lines are for purposes of illustrating environmental structure and form no part of the claimed design.

UNITED STATES PATENT AND TRADEMARK OFFICE
CERTIFICATE OF CORRECTION

PATENT NO. : D683,549 S
APPLICATION NO. : 29/437702
DATED : June 4, 2013
INVENTOR(S) : Patricia Urquiola Hidalgo

Page 1 of 1

It is certified that error appears in the above-identified patent and that said Letters Patent is hereby corrected as shown below:

Title Page, Item (62), replace "Division of application No. 29/419,414, filed on Apr. 27, 2012" with
-- Continuation of application No. 29/419,414, filed on Apr. 27, 2012. --.

Signed and Sealed this
Sixth Day of August, 2013

Teresa Stanek Rea
Acting Director of the United States Patent and Trademark Office
